(**) Term: **14 Years**

CLAIM

(21) Appl. No.: **29/299,038**

The ornamental design for a dual roller lotion bottle, as shown and described.

(22) Filed: **Dec. 18, 2007**

DESCRIPTION

(51) **LOC (9) Cl. 09-01**

FIG. 1 is a perspective view of the dual roller lotion bottle;

(52) **U.S. Cl. D9/726; D9/729**

FIG. 2 is a front elevational view thereof;

(58) **Field of Classification Search D9/529,**

FIG. 3 is a side elevational view thereof;

D9/423, 426, 727, 728, 729; D28/4, 7, 9,

FIG. 4 is a side elevational view thereof opposite that of FIG. 3;

D28/44.1, 77; 206/229; 221/135, 208, 282;

FIG. 5 is a rear elevational view thereof;

222/92, 101, 105, 173, 513, 630; D19/66;

FIG. 6 is a top plan view thereof;

401/209; 601/16; 129/154

FIG. 7 is a bottom plan view thereof;

See application file for complete search history.

FIG. 8 is a perspective view thereof with the cap removed;

(56) **References Cited**

FIG. 9 is a front elevational view thereof;
